UNITED STATES PATENT OFFICE.

HARLAND FANKBONER, OF CHICAGO, ILLINOIS, ASSIGNEE TO THE GOSS PRINTING PRESS COMPANY, OF CHICAGO, ILLINOIS, A CORPORATION OF ILLINOIS.

PRINTING-PRESS.

1,257,838.

Specification of Letters Patent. Patented Feb. 26, 1918.

Application filed January 22, 1917. Serial No. 143,730.

To all whom it may concern:

Be it known that I, HARLAND FANKBONER, a citizen of the United States, and a resident of Chicago, in the county of Cook 5 and State of Illinois, have invented certain new and useful Improvements in Printing Presses, of which the following is a specification, reference being had to the accompanying drawings.

10 My invention relates to rotary printing presses comprising form cylinders equipped with clamping devices movable longitudinally of the cylinder for securing the forms on said cylinder. It is one of the principal 15 objects of my invention to provide a new and improved form and arrangement of parts by reason of which the clamping means must be in clamping position before the press can be started into operation, thus providing against accidental operation of the 20 press with the forms loosely in position upon the cylinders. It is another object of my invention to provide an arrangement which shall prevent the operation of the press so long as the clamp-operating tool is in position upon the clamping devices. It is another 25 object of my invention to provide means serving to retain the clamp-operating tool in position upon the cylinder until the 30 clamps are moved into form-locking position. It is still another object of my invention to improve printing presses in sundry details, particularly in connection with the 35 form-clamping mechanism, as hereinafter specifically pointed out. The preferred means by which I have accomplished my several objects are illustrated in the accompanying drawings and are hereinafter specifically described. That which I believe to 40 be new and desire to cover by this application is set forth in the claims.

In the drawings:

Figure 1 is a fragmentary view showing in dotted lines the end of a form cylinder 45 provided with one form of my improved mechanism;

Fig. 2 is a top or plan view of the end of the cylinder shown in Fig. 1;

Fig. 3 is a side view of the cylinder shown 50 in Fig. 1, being partly in section, being taken on line 3—3 of said Fig. 1;

Fig. 4 is an enlarged detail, being a vertical section taken through the electric switch by which the operation of the press is controlled, as hereinafter described. 55

Fig. 5 is an enlarged detail, being a central vertical section through the guard device shown in Figs. 1, 2 and 3, being taken substantially on line 5—5 of Fig. 2;

Fig. 6 is a view corresponding to Fig. 1, 60 but showing another form of construction;

Fig. 7 is a top or plan view showing the end of the cylinder shown in Fig. 6;

Fig. 8 is a cross-section taken substantially 65 on line 8—8 of Fig. 6, showing the construction of the means for operating and locking the head by which the several clamps are moved in unison;

Fig. 9 is a perspective view of the wrench for operating the clamp-head moving and 70 holding means; and

Fig. 10 is a side view of the end of the cylinder shown in Fig. 6, as seen from the right in said figure.

Referring to Figs. 1 to 5, inclusive, in 75 which corresponding parts are indicated by the same reference characters,

15 indicates the framework of the press in which is journaled the shaft 16 upon which the form cylinder 17 is fixedly mounted. 80 The cylinder 17 is provided with a plurality of plate clamps 18 of any suitable type movable longitudinally of the cylinder by means of adjusting screws 19 which are revolvably connected with said clamps and are 85 adjustably mounted by means of screw-threads in a ring or head 20 fixed upon the cylinder, the construction being such that, upon the rotation of a screw 19 by means of its angular head portion, such screw and the 90 clamp revolvably connected therewith will be moved longitudinally of the cylinder.

Whenever it is desired to place a form in position upon the cylinder 17, such cylinder is brought into position so that the portion 95 of the cylinder upon which the form is to be placed is uppermost, and the curved plate or other suitable form is locked in position upon that side of the cylinder. The cylinder is then given a half revolution so as to bring 100 the opposite portion uppermost, whereupon by a similar operation a suitable form is se-

cured upon that half of the cylinder. It would, of course, be possible to insert a plate in position upon the cylinder upon its lower-most portion, but the ordinary practice comprises the rotation of the cylinder into the convenient position as above set forth.

For the accomplishment of my several objects, I have provided a semi-circular guard 21, such guard being in the form of an angle iron as is best shown in Fig. 5. The lower ends of the curved guard 21 are pivotally mounted upon brackets 22 carried by the framework 15, a spring 23 being suitably connected to said guard and to the frame 15 for holding the guard normally moved to the limit of its motion to the right in Fig. 3, in which position the guard embraces the heads of the screws 19 as is shown in Figs. 2 and 3. As will be readily appreciated, in order to apply a wrench or other suitable tool to the heads of the screws 19, the guard member 21 must be moved toward the left in Fig. 3 against the action of the spring 23.

In order to utilize this movement of the guard 21 for rendering the press incapable of being started until the guard is again moved to the right in said figure into normal position, I have provided an arm 24 upon said guard carrying at its outer end portion the movable member of an electric switch of any suitable type whereby upon the movement of the guard 21 out of normal position an electric circuit shall be broken for rendering the press-driving means inoperative. In the construction shown, the switch comprises a block 25 of any suitable insulating material secured upon the arm 24, such block 25 being provided with a suitable contact member 26 normally held by means of a spring 27 spaced a short distance above the block. The stationary members of the switch in the construction shown comprise contacts 28-29 which are connected by any suitable means with the wires of a controller circuit of any suitable type by which the operation of the press is regulated, the driving means being rendered inoperative, in the construction shown, by the breaking of the circuit through the switch. As is best seen by an inspection of Fig. 3, when the guard 21 is swung to the left in that figure, the arm 24 is moved downward out of contact with a pin 30 which serves normally as a stop for limiting the movement of the guard toward the right. As the block 25 is moved downward therewith out of contact with the members 28-29, serving thus to break the circuit through such members.

By the provision of the protecting means as above described, an operator is prevented from starting the press while a wrench is

in position upon any one of the screws 19 in the uppermost half of the cylinder 17 since such wrench would hold the guard 21 out of normal position. In like manner an operator is prevented from starting the press while any one of the screws 19 in the uppermost portion of the head 20 is in its inoperative retracted position, since the guard 21 would be held out of normal position by such projecting screw so as to cause the circuit through the switch members 28-29 to be held open.

In Figs. 6 to 10, inclusive, which show another form of construction, the parts which correspond to the parts above described are indicated by the same reference characters, but with the addition of an exponent "a". In the construction there shown, the screws 19^a, upon which the plate clamps 18^a are adjustably mounted by means of screw-threads, are journaled in heads 31 which are slidably longitudinally of the cylinder, said heads being adjustable by means of eccentrics 32. A circular guard 33 is employed extending about the uppermost head 31 and having an arm 34 extending downward from its uppermost portion opposite the head 31. The guard 33 is pivotally mounted upon the standard 15^a by means of brackets 35, being held normally at the limit of its movement in clockwise direction in Fig. 10 by means of a spring 36 connecting one of the brackets 35 with the outwardly-extending arm 24^a. As will be readily understood, the head 31 upon the uppermost portion of the cylinder 17^a cannot be moved out of normal locking position by means of the eccentric 32 without first moving the guard 33 to the left in Fig. 10 in order to have access to the eccentric, such movement of the guard 33 serving to open a switch such as that described in connection with Figs. 1 to 5, serving thus to render the press-driving means inoperative so long as the guard is held out of normal position. It is clear that the guard cannot assume normal position until the head 31 and screws 19^a have been returned to normal form-locking position, the press being thus rendered incapable of operation so long as the head 31, the screws 19^a and the clamps 18^a are held out of plate-clamping position. It is also clear that so long as an operating tool is kept in position for operating the eccentric, the press cannot be started, since such tool would serve to prevent the guard from assuming normal position.

In the preferred form of mechanism as shown in Figs. 6 and 7, I provide for retaining the wrench 37 in position in the eccentric 32 during the entire form-locking and unlocking operation. As is shown in Fig. 8, the eccentric 32 is provided with a

slidable key 38 at one side adapted to be moved inward to engage a recess 39 in the shank of the tool 37 so as to hold the tool against withdrawal or to be moved outward 5 into engagement with a suitable recess 40 in the head 31 so as to permit withdrawal of the tool. By providing only one recess 40 and that one located so as to receive the key 38 only when the head is in form-clamping 10 position, withdrawal of the tool is permitted only at that time. As is best shown in Fig. 9, the handles 41-42 of the tool 37 are preferably pivoted upon the shank of the tool, whereby such handles are adapted 15 to be turned down out of the way of the plate or other form being placed upon or taken from the cylinder so as not to interfere with the free and easy manipulation of such plate.

20 What I claim as my invention and desire to secure by Letters Patent, is—

1. In a printing press, the combination of a form cylinder, a screw adjustable longitudinally of the cylinder by means of a 25 suitable operating tool removably applied in operative position for such adjustment, a clamp adapted to be operatively engaged by said screw and removable thereby longitudinally of the cylinder into and out of 30 position for locking a form upon the cylinder, and means effective for preventing the normal operation of the press while said operating tool is in operative position for adjusting said screw longitudinally of the cylinder.

35 2. In a printing press, the combination of a form cylinder, clamps adjustably mounted on the cylinder adapted to engage a form for holding it upon the cylinder, an adjustable member swingingly mounted relative to said cylinder and adapted to be shifted by the locking of the form upon the cylinder, and means controlled by the position of said adjustable member for preventing the 40 press from being started into operation while the form remains unlocked.

45 3. In a printing press, the combination of a form cylinder, clamps adjustably mounted on the cylinder adapted to engage a form for holding it upon the cylinder, means adapted to be actuated by a suitable operating tool for adjusting said clamps, and means adapted to be moved into operative position, by the application of an operating 50 tool to the clamp-adjusting means when the cylinder is in normal position to receive a form, for preventing the normal starting of the press.

55 4. In a printing press, the combination of a form cylinder, clamps adjustably mounted on the cylinder adapted to engage a form for holding it upon the cylinder, means adapted to be actuated by a suitable operating tool for adjusting said clamps, and an

electrical controlling device actuated by the 65 application of the tool for preventing the operation of the press.

5. In a printing press, the combination of a support, a form cylinder revolvably mounted on said support, clamps adjustably 70 mounted on the cylinder adapted to engage a form for holding it upon the cylinder, and a guard movably mounted on said support adapted when in normal position to prevent adjustment of the clamps while the cylinder 75 is in normal position for receiving the form.

6. In a printing press, the combination of a support, a form cylinder revolvably mounted on said support, clamps adjustably 80 mounted on the cylinder adapted to engage a form for holding it upon the cylinder, and an arc-shaped guard pivotally mounted on said support adapted to swing longitudinally of the cylinder and adapted when in normal position to prevent adjustment of 85 the clamps while the cylinder is in normal position for receiving the form.

7. In a printing press, the combination of a form cylinder, clamps adjustably mounted on the cylinder adapted to engage a form 90 for holding it upon the cylinder, a movable guard adapted when in normal position to prevent adjustment of the clamps upon any portion of the cylinder when such portion is in position for having a form clamped 95 thereon, said guard being adapted to be moved out of normal position for permitting adjustment of said clamps, and means controlled by the movement of the guard out of normal position for preventing the 100 starting of the press into operation.

8. In a printing press, the combination of a form cylinder, a head member movable longitudinally of the cylinder, clamps movable with said head member adapted to engage a form for holding it upon the cylinder, an eccentric for controlling the position of said head member, a guard adapted when in normal position to prevent adjustment of said eccentric while such head 110 is in its normal adjusting position for clamping a form upon the cylinder, and means controlled by the movement of said guard out of normal position for preventing the 115 starting of the press into operation.

9. In a printing press, the combination of a form cylinder, a head member movable longitudinally of the cylinder, clamps movable with said head member adapted to engage a form for holding it upon the cylinder, an eccentric for controlling the position of said head member, and means adapted when an operating tool is in operative 120 position relative to said eccentric to prevent the operation of the press.

10. In a printing press, the combination of a form cylinder, clamps adjustably mounted on the cylinder adapted to engage a form

for holding it upon the cylinder, a movable guard adapted when in normal position to prevent ready adjustment of the clamps upon the uppermost portion of the cylinder, 5 an electric switch for controlling the driving of the press, and means actuated by the movement of said guard for operating said switch.

11. In a printing press, the combination of 10 a form cylinder, clamps adjustably mount-

ed on the cylinder adapted to engage a form for holding it upon the cylinder, a movable guard adapted when in normal position to prevent ready adjustment of the clamps upon the portion of the cylinder in position 15 for receiving a form thereon, and an electric switch adapted to be operated by the movement of said guard for controlling the driving of the press.

HARLAND FANKBONER.
